UNITED STATES PATENT OFFICE.

BERTHE GLASER, OF PITTSBURGH, PENNSYLVANIA.

CATAMENIAL SACK.

1,182,007.

Specification of Letters Patent.

Patented May 9, 1916.

Application filed October 30, 1914. Serial No. 869,462.

To all whom it may concern:

Be it known that I, BERTHE GLASER, a citizen of the United States, residing at Pittsburgh, in the county of Allegheny and State of Pennsylvania, have invented certain new and useful Improvements in Catamenial Sacks, of which the following is a specification.

This invention relates to improvements 10 in catamenial sacks and has for its object to provide a simple, efficient, yet sanitary napkin for the use of ladies during the menstrual period.

Another object of the invention is to provide a sanitary napkin and belt, for attaching the same to the body, all in one piece.

Another object of the invention is to provide a napkin having means whereby it may be held folded.

Still another object of the invention is to provide a napkin which may be easily adjusted to persons of different sizes.

With the above and other objects in view I have invented the device illustrated in 25 the accompanying drawings in which,

Figure 1 is a bottom plan view of my invention shown opened, Fig. 2 is a similar view shown folded, Fig. 3 is a perspective view of the device, and Fig. 4 is a section 30 taken on line A—A, Fig. 2.

Like reference characters indicate like parts throughout the specification and in the several views in the drawings in which—

1 indicates a napkin, made preferably of 35 ordinary bath toweling having its four corners cut away, making the napkin octagonal in shape. To the underside 2 of the napkin and lengthwise across its center or body portion 8 are fixed the two ends 3 and 40 4 of a band 5 made preferably of canton flannel; any other desirable material, however, will answer the purpose. The flaps 6 and 7 formed by the opposing sides of the napkin are adapted to be folded over one another and upon said portion 8, under the band 5 which forms a loop slide to receive 45 and hold said flaps in place when the device is to be used.

To one end of the device is secured a 50 loop 9 the ends of which are secured to the corners 10 and 11 of said body portion. The tapes 14 and 15 attached to the opposing corners 12 and 13 of said body are adapted 55 to cross one another through the slide loop 16, which may be readily moved over said tapes in order that portions of said tapes

14 and 15 may be relatively regulated to the waist line of the person to whom the article is to be adjusted. If the person is corpulent or has a large abdomen the portion of the napkin which tapers inwardly of said sliding loop would have to be materially longer than would be the case if the person is thin, and consequently the sliding loop would have to be slid farther from the end 4. The tape 15 should be sufficiently longer than the tape 14 in order that it may be slipped under the loop 9 after passing partially around the body, then the ends 17 and 18 of said tapes will be tied snugly around the body 70 whereupon this device will be held securely in place.

In cases where the flow is abnormal as at such period when it is at its height an additional substance 19 which may be either 75 an ordinary napkin or a wad of absorbent cotton can be placed between the band 5 and the napkin 1, then after the period when this is required is passed the device may be used without the additional member 80 making it more compatible for this means.

Having now described my invention, that 85 which I claim to be new and desire to secure by Letters Patent is:

1. A catamenial sack consisting of an octagonally shaped napkin having a body portion and a flap portion to be folded upon said body portion, a loop formed on one end of said body portion, tapes secured to the opposite end of said body portion and a slide through which said tapes cross 90 whereby said sack may be adjusted snugly to the body.

2. A catamenial sack consisting of an octagonally shaped napkin having a body portion and a flap portion to be folded upon said body portion, a loop formed on one end of said body portion, tapes secured to the opposite end of said body portion and a 100 slide through which said tapes cross whereby said sack may be adjusted snugly to the body, and a band having its ends fixed to the ends of said body portion for holding said flaps folded.

3. A catamenial sack consisting of an octagonally shaped napkin having a body portion and a flap portion to be folded upon said body portion, a loop formed on one end of said body portion, tapes secured to the opposite end of said body portion and a 110 slide through which said tapes cross where-

2
by said sack may be adjusted snugly to the body, and a band having its ends fixed to the ends of said body portion for holding said flaps folded, an additional member adapted to be held between said band and body portion.

4. A catamenial sack consisting of a napkin having flaps adapted to be folded upon its body portion, means for holding said flaps in said folded position, said means consisting of a band fastened at its ends to said body portion, said band forming a loop and an additional member adapted to

be held to said napkin by said band, a loop formed on one end of said sack, means for 15 engaging said loop, said last means consisting of tapes adapted to cross one another, and a sliding loop through which they cross.

In testimony whereof I affix my signature 20 in presence of two witnesses.

BERTHE GLASER.
